PICKER STICK CHECK

Harold H. McClamroch, Concord, N.C.

Application August 21, 1959, Serial No. 835,286

4 Claims. (Cl. 139—163)

This invention relates to a picker stick check for 15 looms, and more especially to an improved form of picker stick check which utilizes a single spring to check the picker stick check motion in both directions and which utilizes an arm and a cooperating stop to adjust the tension on the spring. This improved form of picker stick 20 check is particularly useful on looms for weaving fabrics of artificial fibers, although of course it may be adapted for use on other looms.

There have been many forms of picker stick checks devised, all of which seek to slow and stop the motion of the picker stick as it catches the shuttle when the shuttle enters the box and to check the picker stick when it throws the shuttle. The earlier forms of picker stick 25 checks merely comprised a flexible strap made from a material such as leather or fabric. However the constant friction on the strap made it necessary to reinforce the strap at the point where the picker stick rubbed thereon in order to counteract wear at this point. In addition, the strap absorbed moisture from the air and consequently the yield point of the strap varied depending on the humidity.

There have been devised many types of picker stick checks which utilize spring arrangements acting on the picker stick. While these may obviate the difficulties which are encountered in the picker stick checks which have leather or fabric straps therein, they have usually necessitated the use of one type of spring arrangement to check the motion of the picker stick when it catches the shuttle and another type of spring arrangement to check the motion of the picker stick when it throws the shuttle. The use of two spring arrangements not only results in 30 added complexity in a field already complex, but results in two points at which adjustments must be made to 35 achieve the proper checking action.

In my application Ser. No. 622,946, now Patent No. 2,903,020, I disclose a picker stick check which has a single spring loaded drum on the rear end of the bracket and a strap secured to the drum which extends around the picker stick and is secured to the front end of the bracket. However, the only adjustment in this picker stick 40 check is in the tension of the spring within the drum, or a minor adjustment in the length of the strap permitted by an elongated slot at the end of the strap secured to the bracket. It is obvious that these 45 adjustments must be performed while the loom is not operating, and even then are not very accurate.

It is an object of the present invention to provide a picker stick check which overcomes the drawbacks of the prior art picker stick checks and which utilizes a single spring arrangement with an adjustment means therefor to check motion of the picker stick in both directions.

It is a further object of the present invention to provide a picker stick check in which the proper checking action can be obtained by a single adjustment on the spring arrangement for checking the picker stick in both directions.

Other and further objects of the present invention will become apparent from the following specification and claims taken together with the accompanying drawings, in which:

Fig. 1 is a bottom plan view of one end of the lay of a loom showing the picker stick check according to the invention attached thereto;

Fig. 2 is a side elevation view of one end of the lay of the loom as shown in Fig. 1;

Fig. 3 is an enlarged bottom plan view, partly in section, of the picker stick check according to the invention;

Fig. 4 is a side elevation view, partly in section, of the picker stick check according to Fig. 3;

Fig. 5 is a partial bottom plan view of a modification of the picker stick check according to the invention.

Referring to the drawings, one end of a conventional loom lay 10 has secured to the lower portion thereof a lay plate 11, and on this plate is secured a box front 12. Pivotally secured to the lay at 13 is a pivoted binder 14, the face of which is substantially parallel to the face of the box front 12. In the lay plate 11 between the box front 12 and the binder 14 is a slot 18. A picker stick 16 projects upwardly through the slot between the box front 12 and the binder 14. A conventional picker 17 is secured on the upper end of the picker stick. The picker stick 16 oscillates in the slot 18.

Due to the fact that the shuttle (not shown) enters the box between the box front 12 and the binder 14 at a high rate of speed, it is necessary to provide means for checking the picker stick 16 when the shuttle contacts the picker 17 and moves it to the left in Figs. 1 and 2. If such means were not provided, the impact delivered to the picker stick would force the picker stick back against the extreme left hand end of the slot 18, thus causing wear and breakage of parts. Likewise when the picker stick throws the shuttle it moves toward the right in Figs. 1 and 2 at a high rate of speed, and unless means are provided for checking this motion the picker stick would soon break up on the right hand end of the slot 18 in the lay plate 11.

A bracket 19 having elongated slots 19a and 19b therein is mounted on the bottom of the end of the lay 10 by securing means 11a in the form of nuts and bolts extending through the slots. The elongation of the slots permits adjustment of the position of bracket 19. From one end of bracket 19 depends a check shaft 25 which passes through slot 19c and is secured to the bracket by means of nut 26, a washer 27 being provided between the nut and the bracket. On the lower end of check shaft 25 is a flange 28, and between flange 28 and the bracket is a bearing 29. This bearing is shown as an oilite sleeve bearing, but may be any other suitable bearing, such as a pair of radial thrust bearings, one adjacent the flange and the other adjacent the bracket.

Mounted on the shaft 25 on the bearing 29 is a check body 20 which is made of a good heat conducting material, preferably aluminum. An arresting arm 21 projects from the check body into the path of the picker stick 16. The part of the arresting arm 21 which is struck by the picker stick is lined with a relatively soft lining 23 which will cushion the impact of the picker stick 16 against the check body 20. This lining may be leather or some other similar material.

A projection 30 is formed on the check body 20 and projects radially outwardly of the shaft 25 and parallel to the shaft toward the bracket 19. An adjusting bolt 31 is threaded through the end of projection 30 and has lock nut 32 therearound for locking nut 31 in position on projection 30.

A stop 34 is mounted on the bracket 19 adjacent the periphery of the check body 20, and one end of the bolt

31 abuts stop 34 when the check body 20 rotates sufficiently far clockwise in Fig. 3.

From the other end of the bracket 19 depends a drum shaft 35 in the form of a bolt. Beneath the head 35a of the bolt is an end plate 36 and a spring supporting cylinder 37. The end of the spring supporting cylinder adjacent the bracket 19 bears against a base plate 38 which in turn is secured to the bracket 19. This assembly of parts is secured to the base plate by a nut and washer 35b on the end of the bolt 35 which projects through the base plate 38.

Mounted on the spring supporting cylinder 37 is a spring 39, one end of which is fixed in relation to the cylinder 37 by a bent over end 39a inserted through a hole 37a in the cylinder.

Rotatably mounted on the spring supporting cylinder 37 is a drum 40 having a closed end 40a. An aperture 40b is provided in the drum 40. Inserted through the aperture 40b is the other end of the spring 39 which is also bent over at 39b. One end of a strap 43 is secured to the drum 40 by bent over end 39b of spring 39.

On the end of arresting arm 21 on check body 20 on the end of the bracket opposite the end from which the check shaft 35 depends there is a bolt 44 to which the other end of the strap 43 is secured. The loop of the strap passes around the picker stick 16, as seen in Fig. 1, and the picker stick oscillates within the loop.

In operation, when the picker stick 16 is struck by the shuttle and moves to the left in Fig. 1, the movement is free until the picker stick hits arresting arms 21 and strap 43 begins to stretch tight between the drum 40 and the picker stick 16. At that time the only place for more length of strap to come from is the drum 40. The rearward movement of the picker stick thus starts to unwind the strap 43 from the drum 40 against the action of the spring 39. The more strap that is unwound, the stronger the resisting force of the spring, until the motion of the picker stick is checked. At this point, the spring 39 starts to unwind and moves the picker stick 16 and arresting arm 21 in the forward direction until the spring is no longer tensioned.

When the picker stick 16 moves forward to throw the shuttle, it encounters the front end of the loop of the strap 43 adjacent the drum 40, as shown in Fig. 1. When the adjusting bolt 31 on the check body 20 hits the stop 34, and the strap begins to tighten between the drum 40 and picker stick, the only place from which additional length of strap can come is from the part thereof around the drum 40. This part of the strap is unwound from the drum by the continued forward movement of the picker stick against the action of the spring until the force of the spring resisting the unwinding is sufficient to stop the forward motion of the picker stick. The spring again unwinds and returns the picker stick toward the rear until the spring is no longer tensioned.

It will be seen that by loosening the bolts 11a which secure the bracket 19 to the lay plate 11, the position of the bracket can be adjusted. By threading the adjusting bolt 31 and nut 32 into or out of the projection 30, the tension on the strap 43 can be adjusted. Also, by loosening the nut and washer 35 the cylinder 37 supporting the spring 39 can be rotated to adjust the tension of the spring, and the drum 40 can be moved lengthwise of the bracket 19 in the elongated slot 19c. Thus substantially any position and tension on the strap can be achieved by the proper combination of adjustments.

In the modification shown in Fig. 5, the bolt 31 and the locking nut 32 thereon have been omitted and there has been provided a bolt 45 threaded through the lug 34 and held in place by locking nuts 46. The end of bolt 45 abuts the projection 30, the clockwise movement of the arm 21 being limited by the position of the end of the bolt 45. As can be readily appreciated, the bolt 45 can be adjusted while the loom is running and the arm 21 is oscillating clockwise and counterclockwise.

The advantages of the picker stick check according to the invention are many. Among others, the check can be adjusted by the plurality of adjustments provided thereon, and will remain in the adjusted position. The adjustment of the adjusting bolt can be performed in a very short time, and in the case of the modification of Fig. 5 can even be performed while the loom is in operation. The strap will not be subject to stretching since any force tending to stretch it is transmitted to the spring. The adjustments permit adjustment to provide for any degree of check and any duration of spring action of the picker stick. Because the strap will not stretch, the checking action remains constant and repeated adjustments are unnecessary.

15 Further, when a picker stick check according to the invention is used on a loom the shuttle does not rebound before it should. The shuttle is kept in the right position at all times. Thus when the loom is stopped, for example, the shuttle will not rebound into the box and cause the 20 loom to hand a quill or otherwise cause a "breakout" or "smashup" which damages the cloth and causes considerable delay in production as is often the case with other type checks.

25 It is thought that the invention and its advantages will be understood from the foregoing description and it is apparent that various changes may be made in the form, construction and arrangement of the parts without departing from the spirit and scope of the invention or sacrificing its material advantages, the forms hereinbefore described 30 and illustrated in the drawings being merely preferred embodiments thereof.

What is claimed is:

1. A picker stick check comprising a bracket for mounting on a loom, a check body member of good heat 35 conducting material rotatably mounted on one end of said bracket and having an arresting arm projecting into the path of the picker stick, a stop member on said bracket adjacent said check body, a bolt threaded onto one of said members and engaging the other to limit the rotation 40 of said check body member, means associated with said bolt for locking said bolt in position, a single spring loaded drum rotatably mounted on the other end of said bracket and a flexible strap secured to said drum and wrapped around said drum and extending to and secured 45 to said arresting arm on said check body member.

2. A picker stick check comprising a bracket for mounting on a loom, a check shaft mounted on one end of said bracket, a check body of good heat conducting material rotatably mounted on said shaft and having an 50 arresting arm projecting into the path of the picker stick, a projecting member on said check body projecting radially outwardly of the check shaft, a stop member on said bracket adjacent said check body, a bolt threaded through one of said members and engaging the other to limit the rotation of said check body, means associated with said bolt for locking said bolt in position, a single spring loaded drum rotatably mounted on the other end of said bracket and a flexible strap secured to said drum and wrapped around said drum and extending to and secured 55 to said arresting arm on said check body.

3. A picker stick check as claimed in claim 2 in which said bolt is threaded through said projection and engages said stop.

4. A picker stick check as claimed in claim 2 in which 60 said bolt is threaded through said stop and engages said projection.
